UNITED STATES PATENT OFFICE.

CHARLES C. LORTZ, OF OMAHA, NEBRASKA, ASSIGNOR OF ONE-HALF TO WILLIAM B. LONG, OF OMAHA, NEBRASKA.

SQUARE.

1,068,679.

Specification of Letters Patent. Patented July 29, 1913.

Application filed June 6, 1911. Serial No. 631,506.

To all whom it may concern:

Be it known that I, CHARLES C. LORTZ, a citizen of the United States, residing at Omaha, in the county of Douglas and State 5 of Nebraska, have invented new and useful Improvements in Squares, of which the following is a specification.

This invention relates to squares and more particularly to carpenters' steel 10 squares, the object of the invention being to provide a steel square having the blades foldable upon one another so that they will occupy small space in the tool chest and may be transported from place to place conveniently.

A further object of the invention is to so construct the hinged parts of the square that the strain is removed from the pivotal bolt.

20 Further objects of the invention will appear as the following specific description is read in connection with the accompanying drawing, which forms a part of this application, and in which—

25 Figure 1 is a fragmentary elevation showing the square in open position. Fig. 2 is a similar view with the square in closed position. Fig. 3 is an inside elevation of the tongue. Fig. 4 is a similar view of the 30 blade.

Referring more particularly to the drawing, 1 represents the blade of the square and 2 the opposite blade or tongue. The blade 1 is provided with a right angularly extending hinge member 3 which is circular, 35 as at 4, on its outer edge. Formed on the right angular extension 3 are ribs 5 and 6 and between the ribs 5 and 6 an annular groove 7 and within the rib 6 a circular 40 socket 8. Outside of the rib 5 the extension is reduced to form a circular track 9 for the rib 10 upon the tongue 2. This rib 10 corresponds with a similar rib 11 separated therefrom by a groove 12 and inside of the 45 rib 11, and separated therefrom by a groove 13, is a central stud 14 adapted to engage the socket 8. The stud 14 is centrally apertured and screw threaded to receive a pivoting screw 15 which passes through a countersunk hole 16 arranged in the extension 3 50 coincident with the socket 8.

Extending through the extension 3 and

the end of the tongue 2 are suitable apertures 17 and 18, arranged at quartering intervals through the rib 5 and within the 55 groove 12 respectively. Within the apertures 18 of the stud 5 are permanently positioned and secured therein steel pegs or pins 19, said pins may be suitably secured in any well known manner, such as solder or 60 the like. These pins are adapted to register with the apertures 17 when the square is adjusted to either open or folded position. This function is accomplished by the loosening of the pivoting screw 15 and by a slight 65 lateral adjustment. The projecting portion of the steel pegs or pins 19 may be readily withdrawn and inserted in the respective apertures 17 of the other blade member 2, by accomplishing this, a positive locking 70 action is obtained between the parts 1 and 2 in either position.

Having thus described the invention, what I claim as new is:—

A square comprising a pair of blades, one 75 of said blades being provided with a right angular hinge extension having a circular outer edge; a bolt for pivoting the other blade to the hinge extension, a pair of relatively spaced circular ribs formed on the 80 extension, one of said ribs being provided with a series of apertures, and the said ribs having therebetween an annular groove, a circular track disposed outside and concentric with the rib having the apertures, 85 the other blade being formed with a series of annular ribs and grooves adapted for interlocking engagement with the ribs and grooves of said angular extension, the said other blade having a series of apertures disposed in one of its grooves and arranged at quartering intervals and pins permanently seated in the apertures of the ribs and adapted to enter the apertures in the grooves of the other of said blades, whereby a positive locking action is obtained between the 90 blades in either open or closed position. 95

In testimony whereof I affix my signature in presence of two witnesses.

CHARLES C. LORTZ.
